PREPARATION OF TETRAHYDROPRIMIDINES
Joseph J. McBride, Jr., Panama City, Fla., and Eugene J. Miller, Wheaton, Ill., assignors to Armour and Company, Chicago, Ill., a corporation of Delaware
No Drawing. Continuation-in-part of application Ser. No. 328,194, Dec. 5, 1963. This application Jan. 23, 1967, Ser. No. 610,759
5 Claims. (Cl. 260—251)

ABSTRACT OF THE DISCLOSURE

A process for preparing tetrahydropyrimidines comprising reacting β -cyanoethyl aliphatic amines with an acylating agent, hydrogenating the N-acyl-N- β -cyanoethyl aliphatic amine to produce acyl-N-aliphatic-1,3-propanediamine, and bringing about closure of a 6 membered ring by heating the diamine in the presence of a metal catalyst or the salts thereof. The ring closure is especially satisfactory when conducted in the presence of nickel, copper, cobalt, manganese, platinum, palladium and the chloride, bromide, iodide, oxide, sulfate, carbonate, and acetate salts thereof, in the presence of a strong base at a temperature of about 170–230° C.

CROSS-REFERENCE TO RELATED APPLICATION

This application is a continuation-in-part of our prior application Ser. No. 328,194, filed Dec. 5, 1963, now abandoned.

BACKGROUND OF THE INVENTION

(1) Field of the invention

This invention relates to a process for the production of tetrahydropyrimidines by a three step process:

- (1) Acylating a β -cyanoethyl aliphatic amine, then
- (2) Catalytic hydrogenation to form acyl-N-aliphatic-1,3-propanediamine, and
- (3) Catalytic ring closure to yield 3-aliphatic-2-substituted-3,4,5,6-tetrahydropyrimidine.

(2) Description of the prior art

Prior art methods of forming 2-substituted tetrahydropyrimidines have been the reaction of a monocarboxylic acid and a 1,3-propane diamine at temperatures within the range of 250°–300° C. to produce cyclization. The lower temperature of about 250° C. has been utilized for ring closure when a chemical dehydrating agent has been employed. Even with the rigorous reaction conditions, these reactions required long periods of time.

3-aliphatic-2-substituted tetrahydropyrimidines have been formed by heating equal moles of acetic acid and a N-aliphatic 1,3-propanediamine at high temperatures to form the amide and then heating at about 250–300° C. and with a dehydrating agent to cyclize the monoamide to form the tetrahydropyrimidine. This reaction, even with the rigorous reaction conditions, results in low product yield due to the formation of diamide and difficulty in ring closure of the monoamide which is formed.

SUMMARY

An object of this invention is to provide an improved process for the preparation of tetrahydropyrimidines, and intermediates and derivatives thereof, with higher yields and fewer side reactions than in previous methods of preparations. A further object is to provide an improved process for the preparation of 3-aliphatic, 2-aliphatic or aromatic, 3,4,5,6-tetrahydropyrimidines and intermediates thereof through the formation of the acylated diamines and the use of metal catalysts for ring closure.

2

Other specific objects and advantages will appear as the specification proceeds.

In one embodiment of our invention, we react a β -cyanoethylaliphatic amine having from 8 to 22 carbon atoms which may be a straight or branched chain, saturated or unsaturated, with an aliphatic or aromatic acylating agent, such as an acid halide or acid anhydride, and then hydrogenating the resulting N-acyl-N- β -cyanoethyl amine over a nickel catalyst in the presence of a base. The resulting acyl-N-alkyl-1,3-propanediamine is then heated to yield the tetrahydropyrimidine product. In the final step, the acyl-N-alkyl-1,3-propanediamine may be distilled, preferably in vacuo, at a temperature of about 170–230° C. in the presence of a metal catalyst, such a nickel, copper, cobalt, manganese, platinum, palladium, and salts thereof, and preferably in the presence of a strong base selected from the group of potassium hydroxide, sodium hydroxide, calcium hydroxide, etc. Particularly useful catalysts may be selected from the group consisting of nickel, copper, cobalt, manganese, platinum, palladium, and the chloride, bromide, iodide, oxide, sulfate, carbonate, and acetate salts thereof. From about 0.5 to 5 weight percent catalyst is preferred. The use of the catalysts has been found to be extremely effective in bringing about ring closure.

By way of illustration, the following specific example may be set out in detail, the example dealing with the preparation of 3-dodecyl-2-methyl-3,4,5,6-tetrahydropyrimidine, and the sequence reactions being set out as follows:

(1) β -cyanoethyldodecylamine was acylated with acetyl chloride.

(2) The product of reaction #1 was hydrogenated.

(3) The product of reaction #2 was cyclized by distilling in vacuo at 200° C. in the presence of a metal catalyst.

In Step 1 of the above reaction, β -cyanoethyldodecylamine was allowed to react with acetyl chloride, the resulting N-acetyl, N- β -cyanoethyldodecylamine was hydrogenated over a nickel catalyst in the presence of caustic. The product of the second reaction, namely, acyl-N-dodecyl-1,3-propanediamine, was distilled in the presence of copper chloride at 200° C. in vacuo to yield 3-dodecyl-2-methyl-3,4,5,6-tetrahydropyrimidine. As an alternate to the third step described above, the substituted 1,3-propanediamine was distilled at a temperature of from 180–200° C. at 0.1–0.15 mm. in the presence of Raney nickel to cyclize the substituted 1,3-propanediamine. The metal catalyst may also be packed in a heated column and the diamine run through the column to achieve cyclization. The use of the nickel or other metal catalyst as described above has been found to be very effective for ring closure reaction. Heretofore the ring closure has been effected only by extremely high temperatures, strong dehydrating agents, and long reaction times. We believe that the metallic ion may function as a chelating agent which

moles) was added slowly, with stirring, over a period of 90 minutes. The temperature of the reaction mixture was maintained at 23-28° C. by external cooling. The mixture was stirred for an additional hour after the addition was completed. The acetic acid liberated in the reaction was removed by stripping at 75° C. at 1 mm. Hg until the acid value dropped to 8.

The product was obtained as a pale yellow oil in almost quantitative yield, 1,261 g.

EXAMPLE VI

N-acetyl-N'-octyl-1,3-propanediamine was prepared as follows:

A one-liter, stainless steel stirred autoclave was charged with N-acetyl-N-cyanoethyloctylamine (573 g., 2.56 moles) and Raney nickel catalyst (11.5 g. 2% by weight, alcohol washed). Ammonia was charged to a pressure of 125 p.s.i.g. at room temperature and the reaction mixture then heated to 130° C. Hydrogen was then added to a total pressure of 800 p.s.i.g. The temperature and pressure were maintained at 130-150° C. and 800 p.s.i.g. for 3-4 hours. The reaction product was filtered to remove the catalyst, then stripped under aspirator vacuum for 2 hours at 55° C.

The product was obtained as an amber oil in 98% yield, 573 g.

Analysis.—NE, 215 (calcd. 228); PA, 5.7%; SA, 93.5%; TA, 6.8%.

EXAMPLE VII

N-octyl-2-methyl-3,4,5,6-tetrahydropyrimidine was prepared as follows:

N-acetyl - N'-octyl-1,3-propanediamine (567 g., 2.49 moles) was subjected to distillation over 1% by weight CuCl₂·2H₂O (5.67 g.) and 3 pellets KOH through a 12-inch Vigreux column. The material distilling at 130-153° C./3-3.5 mm. was collected as a pale yellow oil (403 g., 77% yield).

Analysis.—NE, 204.8 (calcd. 210.3); TA, 87.4%.

EXAMPLE VIII

N-acetyl-N-cyanoethyloctadecylamine was prepared as follows:

A five-liter, creased flask, equipped with mechanical stirrer, addition funnel, and thermometer, was charged with cyanoethyloctadecylamine (976 g., 3.04 moles) and one-liter of ether. Acetic anhydride (346.8 g., 3.4 moles) was added slowly, with stirring, over a period of one hour. The temperature of the reaction mixture was maintained at 25-30° C., by external cooling. A thick white solid was formed during the addition, requiring additional solvent to keep the mixture as a slurry. The mixture was stirred for an additional 40 minutes after the addition was complete. The reaction product was diluted with petroleum ether, cooled, and filtered to yield 845 g. (77.5% yield) of white solid, AV=3.

EXAMPLE IX

N-acetyl - N'-octadecyl-1,3-propanediamine was prepared as follows:

A one-liter, stainless steel autoclave was charged with N-acetyl - N-cyanoethyloctadecylamine (361.4 g., 0.99 mole) and Raney nickel (7.2 g. 2% by weight alcohol washed). Ammonia was charged to a pressure of 125 p.s.i.g. at room temperature and the reaction mixture heated to 130° C. Hydrogen was then added to a total pressure of 800 p.s.i.g. Temperature and pressure were maintained at 130° and 800 p.s.i.g. for 3.5-4 hours. The catalyst was removed by filtration and excess ammonia stripped under reduced pressure.

The product was obtained in almost quantitative yield.

Analysis.—NE, 362 (calcd. 368); PA, 4.4%; SA, 97.1%; TA, nil.

EXAMPLE X

N-octadecyl - 2 - methyl-3,4,5,6-tetrahydropyrimidine was prepared as follows:

N-acetyl-N'-octadecyl-1,3-propanediamine (622 g., 1.69

moles) was subjected to distillation over 1% by weight CuCl₂·2H₂O (6.2 g.) and 3 pellets of KOH through a 12-inch Vigreux column. The material distilling at 203-219° C./0.5-0.7 mm. was collected as a pale yellow oil which solidifies slowly on standing, 511 g. (86% yield).

Analysis.—NE, 342.5 (calcd. 350); PA, 5.5%; SA, 5.1%; TA, 92.0%.

EXAMPLE XI

10 N-benzoyl-N-cyanoethyldodecylamine was prepared as follows:

N-1-cyanoethyldodecylamine (261.2 g., 1.09 moles), aqueous sodium hydroxide (51.4 g. in 117 ml. water) and 800 ml. of methylene chloride were charged into a five-liter, three-necked flask. Benzoyl chloride (150.9 g., 1.22 moles) was added slowly over sixty minutes at 5° C. The reaction mixture was then stirred for an additional ninety minutes at 5-10° C. The organic layer was separated, washed several times with water and dried over anhydrous sodium sulfate. Methylene chloride was distilled off under reduced pressure to yield 352 g. (94.4%) of product with a residual acid value of 4.1.

EXAMPLE XII

25 Benzoyl-N-dodecyl-1,3-propanediamine was prepared as follows:

A 300 ml. stainless steel stirred autoclave was charged with N-benzoyl-N-cyanoethyldodecylamine (162 g., 0.47 mole) and Raney nickel catalyst (16.2 g. 10% by weight alcohol washed). Ammonia was added to 150 p.s.i./30° C., then hydrogen to a total pressure of 400 p.s.i./30° C. The temperature was raised to 130° C. and the total pressure increased to 2000 p.s.i. with hydrogen. The reduction required 10-11 hours, yielding 150 g. (92.5%) of crude benzoyl-N-dodecyl-1,3-propanediamine.

Analysis.—Neut. equiv., 510 (calcd. 344); PA, 13.7%; SA, 42.6%; TA, 12.4%.

Infrared analysis shows no nitrile present.

40 The primary and secondary amine represents the two isomeric benzoyl - N - dodecyl - 1,3 - propanediamine. The tertiary amine is probably some tetrahydropyrimidine formed during the reduction. The high neutralization equivalent is due to the presence of a neutral material, probably N-dodecylbenzamide, formed by decyanoethylation of the starting material.

EXAMPLE XIII

50 N - dodecyl - 2 - phenyl - 3,4,5,6 - tetrahydropyrimidine was prepared as follows:

Crude benzoyl - N - dodecyl - 1,3 - propanediamine (141.0 g. containing about 20% dodecylbenzamide) was distilled over 1% CuCl₂ and a trace of potassium hydroxide at 190-220° C./1 mm. to yield 86.8 g. of crude N-dodecyl - 2 - phenyl - 3,4,5,6 - tetrahydropyrimidine.

Analysis.—Neut. equiv. 538 (calcd. 328), PA+SA = 1.0%, TA = 56.7% (as tetrahydropyrimidine).

60 The dodecylbenzamide in the above was removed by crystallization from Skellysolve B and the tetrahydropyrimidine thus obtained redistilled as above to give 50 g. (37.5% crude yield) of a yellow oil.

Analysis.—Neut. equiv. 405 (calcd. 328), PA+SA = 1.0%, TA = 81.6%.

65 Infrared analysis indicated the product to be predominantly tetrahydropyrimidine with some monosubstituted amide present.

EXAMPLE XIV

70 The catalyst effect of the various materials was determined by distillation of the N - acetyl - N' - dodecyl - 1,3 - propanediamine in the presence of the catalyst and determining the amount of tetrahydropyrimidine in the distillate. This information is summarized in the following table:

Compound R=C ₁₂ H ₂₅	Catalyst	Analysis before distillation			Analysis after distillation				Percent of change distilled
		N.E.	Sec. amide	Sec. amine	N.E.	Sec. amide	Sec. amine	Pyrimidine	
								Wet	IR
RNH(CH ₂) ₃ NHC ₂ H ₅	None	100.7	95.6	278				24.9	
RNH(CH ₂) ₃ NHC ₂ H ₅	CuSO ₄	100.7	95.6	287				64.3	
RNH(CH ₂) ₃ NHC ₂ H ₅	KOH	100.7	95.6	268	43.5	43.3	41.5	48.4	96.6
RNH(CH ₂) ₃ NHC ₂ H ₅	CuSO ₄ KOH	287.5	101.3	98	261			68.8	
RNH(CH ₂) ₃ NHC ₂ H ₅	CoCl ₂ KOH	100.7	95.6	266.5	24	21.8	59.5	66.6	90
RN(CH ₂)CN COCH ₃ *	Ni(R)KOH	308	61.5	68.4	266			68.4	77.9
Reduction product									ca. 80

*IR analysis shows 35% primary amine. The reduction product consists of a mixture of 6% tetrahydropyrimidine and 76% of a mixture of R-NH(CH₂)₃NHC₂H₅ and R-N(CH₂)₃NH₂.

EXAMPLE XV

N - (β - cyanoethyl) - N - Isobutyldodecylamine was prepared as follows:

A one-liter, four-neck creased flask equipped with a mechanical stirrer, thermometer, addition funnel and reflux condenser was charged with 217 g. (0.80 mole) of N-(β-cyanoethyl) dodecylamine. Isobutyric anhydride (139 g., 0.88 mole) was added at 23-30° C. over a 30 minute period, then the reaction mixture stirred overnight at room temperature. The entire reaction mixture was dissolved in ether and washed seven times with water and aqueous KOH to remove any free acid. The ether was stripped off under reduced pressure and 249.2 g. (92% mass yield) of product was obtained, leaving an acid value of 1.8.

EXAMPLE XVI

N - (β - cyanoethyl) - N - Isobutyryldodecylamine was reduced as follows:

A one-liter pressure reaction vessel was charged with 245.8 g. of N - (cyanoethyl) - N - isobutyryldodecylamine and 9.8 g. (4% by wt.) of alcohol washed Raney nickel catalyst. Ammonia was then added to 125 p.s.i.g. at room temperature and the temperature raised to 135° C. The total pressure was made up to 800 p.s.i.g. at 135° C., with hydrogen. The reaction temperature and pressure was maintained for two hours, then cooled and filtered to give 239.6 g. (97.2% mass yield) of product having the following analysis:

NE=254 (calcd. 314), PA=76.7%, SA=11.4%, TA=11.9%.

EXAMPLE XVII

N - dodecyl - 2 - isopropyl - 3,4,5,6 - tetrahydropyrimidine was prepared as follows:

The reduction product obtained in Example XVI (231 g.) was distilled over 1% (by wt.) CuCl₂ and 2-4 KOH pellets through a Claisen head distillation column. A fraction distilling at 170-193° C./1.0-2.4 mm. was obtained representing 124.6 g. or 51.9% of the charge having the following analysis: NE=237 (calcd. 256), TA=66.3%.

EXAMPLE XVIII

Various copper salts were used as catalysts for cyclization of N - dodecyl - N' - acetyl - 1,3-propanediamine, or

its corresponding isomer, to N - dodecyl - 2 - methyl - 3,4,5,6 - tetrahydropyrimidine. In each case distillation was carried out using a 35-40 gm. charge over 1 wt. percent of the copper salt and 1-2 KOH pellets. Distillation temperatures were in the range of 170-230° C./0.3-1.0 mm.

The starting material had the following analysis: NE=286 (calcd. 284.5), PA=61.0%, SA=30.0%, TA=7.9%.

The results are shown in the following table:

PREPARATION OF N-DODECYL-2-METHYL-3,4,5,6-TETRAHYDROPYRIMIDINE

Catalyst	Percent Distilled	Percent TA ¹	Percent SA ²	Percent PA ³
Cu(O ₂ CCH ₃) ₂	77.0	64.5	22.0	15.8
CuI ₂ H ₂ O	85.0	74.5	22.0	5.7
CuO	79.0	74.5	23.0	7.6
CuCO ₃	80.0	79.8	14.4	8.4

¹ Tertiary amine represents the amount of tetrahydropyrimidine present.

² Percent Secondary amine.

³ Percent Primary amine.

While in the foregoing specification we have set forth procedural steps and treating materials in considerable detail for the purpose of illustrating our invention, it will be understood that such detail or details may be varied widely by those skilled in the art without departing from the spirit of our invention.

We claim:

- In a process for preparing tetrahydropyrimidines, the step of heating a compound selected from the group consisting of alkanoyl- and mono carbocyclic aroyl-N-aliphatic-1,3-propanediamine wherein the aliphatic group has from 8 to 22 carbon atoms in the presence of a catalyst selected from the group consisting of nickel, 65 copper, cobalt, manganese, platinum, palladium, and the chloride, bromide, iodide, oxide, sulfate, carbonate, and acetate salts thereof, in the presence of a strong base at a temperature of about 170-230° C. at subatmospheric pressure.
- The process of claim 1 wherein said diamine is 70

75 2. The process of claim 1 wherein said diamine is

selected from the group consisting of acetyl- and benzoyl-N-aliphatic-1,3-propanediamine.

3. The process of claim 1 wherein said catalyst is present in from about 0.5 to 5 weight percent.

4. The process of claim 1 wherein said catalyst is 5 selected from the group consisting of copper chloride and Raney nickel.

5. The process of claim 1 wherein said base is selected from the group consisting of potassium hydroxide, sodium hydroxide and calcium hydroxide.
